Joseph Piencro, his Heirs, etc. vs. New Hampshire
Letters Patent.

The Schedule referred to in these Letters Patent and making part of the same containing a description in the words of the said Joseph Piencro by himself of his improvement in the Machine for sawing wood.

To all to whom these presents shall come. Be it known, that Joseph Piencro, of Hanover in the County of Grafton and State of New Hampshire, have invented a new and useful improvement in the machine for sawing wood, denominating the balance wheel wood saw machine, and that the following is a full and exact description thereof: I make an outside frame about five feet high, and four feet square, two studs are then added one on each side of the outside frame into which wood near the bottom is framed a cross piece; into this cross piece are framed two inside studs running from it to two other cross pieces at the top of the frame which run the other way of it on the top cross pieces and on one side of the frame are placed three iron railings. The saw is then hung on one end of a shaft, and a balance wheel and a wheel on the other end with two bearings, one near the saw, and the other between the wheel and balance wheel. I then place a carriage or platform on the frame with a space underneath for the saw to run; and with two bows, one on the edge, and one near the middle, which run on the three railings, a handle or lever is then made with a spaccet cut for the saw to run in crooked at one end, with one tooth near the middle to hold the wood, and hinged at the other end, and is hung on the carriage or platform on each side near the center of the saw on the carriage or platform, and under the handle or lever is placed, which is held firmly by the handle

and passed up to the rear, a casing is then made to cover the rear and is fastened to the carriage or platform, another casing is made for the balance wheel and fastened to the frame, both casings are designed for safety in using. The propelling power is applied to said machine by a band connecting the wheel with said power, it is to be understood that the proportions of the different parts of the machine can be varied at pleasure. What I claim as my improvement is the construction of the handle or lever; the manner of holding down the road; the three railway ways which the carriage or platform runs backward & forward, together with the general arrangement of the different parts of the whole machine; and the application of the balance wheel to a circular disc propelled by an endless chain horse power, that kind of power being specifically calculated to take advantage of the head way of a balance wheel.
